QUICK ACTING SHUT-OFF VALVE FOR OIL BURNERS, ETC

Filed Dec. 6, 1922

FIG. 1

UNITED STATES PATENT OFFICE.

ROBERT D. MCINTOSH, OF RIVER FOREST, ILLINOIS, ASSIGNOR TO THE IMPERIAL BRASS MANUFACTURING COMPANY, OF CHICAGO, ILLINOIS, A CORPORATION OF ILLINOIS.

QUICK-ACTING SHUT-OFF VALVE FOR OIL BURNERS, ETC.

Application filed December 6, 1922. Serial No. 605,232.

My invention is concerned with a valve designed especially for oil burners, and is designed to equip the same with a quick-acting safety valve whereby if the pilot light 5 is accidentally extinguished and it is attempted to start up the burner by turning on the oil supply, either manually or automatically by a thermostat control, the supply so turned on will be certainly and completely 10 cut off before any substantial amount of oil has flowed through the burner.

To this end, it consists of a bucket connected to a lever controlling a quick-acting shut-off valve placed in the supply line, the 15 bucket being located adjacent the discharge end of the overflow pipe of the oil burner, so that when a sufficient weight of the overflowed oil has entered the bucket, the quick-acting shut-off valve will be tripped and the 20 oil-supply line instantly and completely shut off.

To illustrate my invention, I annex hereto a sheet of drawings, in which the same reference characters are used to designate identical parts in all the figures, of which, 25

Fig. 1 is a perspective view of a portion of an oil burner having my invention applied thereto;

Fig. 2 is a side elevation of the safety valve 30 and the attached bucket;

Fig. 3 is a front elevation as seen from the line 3—3 of Fig. 2; and

Fig. 4 is a vertical section as seen on the section line 4—4 of the same figure.

35 10 represents a portion of a furnace having an oil burner connected therewith, which oil burner is supplied from the pipe 11 having the adjusting valve 12 therein by which the rate of the feed of the oil can be controlled. As is well known, these oil burners are supplied with a pilot light, and also with an overflow pipe 13 from the lower end of which the oil will be discharged in case it is not burned. The mechanism thus far 45 described may be of any ordinary construction and, per se, forms no part of my invention.

In the supply line 11, I locate the shut-off valve 14, which consists of a valve casing in 50 the general shape of a cross, with the supply entering through the pipe 11 screwed therein and through the small port 15 which opens into the internally-threaded chamber 16, which is closed at its lower end by the cap

screw 17 threaded therein. At the top of 55 the chamber 16 is the annular valve-seat 18, which forms the bottom of the passage 19 connecting the chamber 16 with the outlet port 20, opening into the continuation of the pipe 11 threaded into that end of the valve 60 casing. The valve is shown in Fig. 4 as open, the valve consisting of the stem 21 having secured on the lower end thereof the valve disk 22 held in place by the nut 23 threaded on the lower end of the valve stem 65 21. The disk 22 is provided with the leather or rubber washer 24 which engages the valve seat 18. A helically-coiled expanding spring 25 located in the hollow of the cap screw 17 and having its upper end engaging the under 70 side of the valve 22 tends to close the valve, but is normally restrained from doing so by the position of the bucket 26 and its connections, which will now be described. The bucket 26 is suspended by the bail 27 from 75 the power end of the lever 28, which is fulcrumed by the screw 29 to the ear 30 projecting from the valve casing 14. The normal position of the valve is controlled by the set screw 31 threaded through the body of 80 the valve and engaging the bottom of the cap screw 17. A lock nut 32 serves to secure the set screw 31 in any position to which it may be adjusted, and it will be understood that the position of the set screw 31 controls the 85 amount of movement that has to be given to the lever 28 before the quick-acting closure of the valve occurs. Pivoted to the lever 28 by the screw 33 is a link 34 pivoted at its upper end by the screw 35 to the lever 36, 90 which is fulcrumed by the screw 37 between the ears 38 formed on the top of the valve casing 14. The lever 36 bears on the upper end of a plunger 39, which has its enlarged, rounded lower end 40 engaging the flexible 95 diaphragm 41, which is preferably composed of rubber reinforced by fabric, and taking the shape of a concave disk with its edges resting on the annular seat 42 formed in the top of the valve casing 14 and held in place 100 by the metal ring 43 resting thereon, which in turn is held in place by the hollow nut 44 screwed into the top of the casing 14 and having the squared end 45 by which it may be turned. It will be understood that the 105 stem of the plunger 39 passes loosely through the central aperture of the nut 44, so that there is no friction to impede the movement

of the plunger 39 once its movement becomes possible.

The operation of the device will now be apparent: The apparatus is normally set as shown in full lines in Fig. 2, and in this position the oil supply can flow in through the port 15, up through the channel 19, and out through the port 20. In case there is any overflow of the oil from the pipe 13 into the bucket 26, the weight of the oil will eventually swing the lever 28 downward about its fulcrum 29 until the center line of the link 34 passes the center of the pivot 29, thus breaking the toggle joint, after which the spring 25 acting through the valve stem 21, diaphragm 41, plunger 39, lever 36 and link 34, will suddenly swing the lever 28 and the attached bucket 26 to the dotted-line position shown in Fig. 2, thus leaving the spring 25 free to hold the valve 22 seated firmly against the annular seat 18, thus completely and instantly shutting off the flow of the oil through the supply pipe 11. Owing to the fact that the bucket 22 is moved so rapidly by the action of the spring, there is a tendency to throw the oil out of the bucket, and, to counteract this, I provide it with the annular funnel-shaped cover 46, which may be permanently secured thereto, and which has the central aperture sufficient to admit the oil, but not allowing any substantial quantity of it to be thrown out during the rapid movement of the bucket 26 from the full-line to the dotted-line position shown in Fig. 2.

35 While I have shown the novel quick-acting valve as applied to an oil burner, it will be

understood that the valve per se might be used in different combinations; and it will also be understood that, while I have shown and described my invention as embodied in the form which I at present consider best adapted to carry out its purposes, it is capable of modifications, and that I do not desire to be limited in the interpretation of the following claims except as may be necessitated by the state of the prior art.

What I claim as new, and desire to secure by Letters Patent of the United States, is:

In a quick-acting valve, the combination with a cross-shaped valve-casing having an inlet port in one end, an outlet port at the opposite end, chambers in the intermediate ends, a passage between the chambers, a valve seat at one end of the passage, a valve therein having a stem sliding through the passage, a helically-coiled expanding spring in the chamber with the valve and tending to seat it, a diaphragm in the other chamber, an opening from the other chamber, a plunger engaged by the diaphragm and extending and moving through the opening, and controlling means engaging the outer end of the plunger, said controlling means consisting of a pair of levers connected by a link, one of said levers engaging the plunger and the other having its fulcrum so located that its movement swings the link across its fulcrum point to release the dead center and permit the spring to act to close the valve.

In witness whereof, I have hereunto set my hand this 4th day of December, 1922.

ROBERT D. McINTOSH.
